United States Patent Office

Des. 229,112
Patented Nov. 6, 1973

229,112

SANITARY NAPKIN HOLDER

Masataka Susuki, Sapporo, Japan, assignor to Daiichi Seiyaku Co., Ltd., Tokyo, Japan

Filed Aug. 24, 1971, Ser. No. 174,585

Term of patent 14 years

Int. Cl. D28—01

U.S. Cl. D83—1 A

FIG. 1

FIG. 2

FIG. 4

FIG. 1 is a top plan view of a sanitary napkin holder showing my new design,

FIG. 2 is a sectional view along line 2—2 of FIG. 1,

FIG. 3 is a perspective view thereof, and

FIG. 4 is a perspective view of a modified form thereof.

The grille cloth fragmentarily shown by criss-cross lines is continuous within the boundaries indicated.

I claim:

The ornamental design for a sanitary napkin holder, as shown and described.
